UNITED STATES PATENT OFFICE.

ALLEN B. MORRIS, OF MARSHALLTOWN, IOWA.

MITER-BOX.

No. 798,818.

Specification of Letters Patent.

Patented Sept. 5, 1905.

Application filed October 24, 1904. Serial No. 229,699.

To all whom it may concern:

Be it known that I, ALLEN B. MORRIS, a resident of Marshalltown, in the county of Marshall and State of Iowa, have invented 5 certain new and useful Improvements in Miter-Boxes, of which the following is a full, clear, and exact description.

The invention designs to provide an improved miter-box of simple and compact construction; further, to provide an improved device of this character which can be readily adjusted for cuts of different angles and can be folded for convenience in packing or transportation when not in use, and, further, to 15 provide an improved miter-box.

The invention consists of the several novel features of construction hereinafter set forth, and more particularly pointed out by claims at the conclusion hereof.

20 In the drawings, Figure 1 is a perspective of a miter-box embodying the preferred form of the invention. Fig. 2 is an inverted plan view, parts being shown in position for a right-angle cut. Fig. 3 is a similar view, 25 parts being shown in folded position. Fig. 4 is a view in vertical section on line 4-4 of Fig. 2. Fig. 5 is a horizontal section on line 5-5 of Fig. 4.

The miter-box embodies a frame or support 30 A, which comprises a pair of members a a, secured together by a bolt or rivet a'. Between said members a space is formed in which a saw is guided. Each of said members comprises a base-bar a', an upright a'', and a 35 top bar a'', which are preferably integrally formed. A side guide B is pivotally secured to each member of the support A and on opposite sides of said support, respectively. Guides B are pivotally sustained by a top lug

40 b and a bottom lug b' of support A and pivot-bolts b'', about which the side guides can be adjusted into any desired angle with respect to the saw-guide to vary the angle of the cut. The side guides are equidistantly adjusted 45 about their respective pivots, so that like angle-cuts will be made on both strips of a joint. Guides B are held in assigned position with respect to the saw-guide by a pair of links C C, each of which has one end pivoted

50 at c to the lower edge of one of the guides B and its other end pivoted to a connecting-stud c', which is secured to an adjustable block c''. Said block is held between the base-bars of the saw-guide and has its sides grooved, as at c'', to receive the correspondingly-shaped inner edges of said bars, so the blocks will be

held against vertical displacement. Said block is movable longitudinally between the base-bars, and a clamp-screw D is adapted to force bars a together, so block c'' will be securely 60 clamped in assigned position therebetween. Said clamp-screw extends through an ear a'' of each base-bar and is provided with a screw-thread engaging a corresponding thread in one of said ears. By adjustment of block c'' 65 the side guides will be equidistantly shifted with respect to the saw-guide, so the angle of the cut will always be one-half of the angle of the side guides. The clamp holds the block in assigned position. 70

A bottom or rest E is pivotally connected to each of the side guides. Each bottom has secured to each of its end guides a strap e. Pivots e' extend through projecting lugs e'' of side guides B and one of the straps, and thus 75 connect the side guides and the rests. Each bottom support or rest being hinged to the side guides is adjustable therewith and can furthermore be snugly folded into parallel 80 relation with respect to the guides, as shown in Fig. 3, for convenience in transportation, and so the device can be conveniently placed in a tool-chest when not in use. The rests are arranged so they will abut against base-bar of the frame and position the side supports for a right-angle cut. 85

When the device is to be used, the angle whereinto two strips are to fit is first measured by a protractor or other suitable tool. The side strips are then placed into position 90 to correspond to the measured angle and are secured in assigned position by clamp-screw D. The strip or board to be cut is then placed into the corner between the rest and the side guides at one side of the saw-guide. 95 The cut then made by the saw will be one-half of the desired angle and connect to form a true miter-joint. The other strip of a joint is then placed into the other support. Thus each of the strips will be cut to form a true 100 miter-joint. Each rest is cut away, as at e', to leave the links free for adjustment and so the bottom can properly rest on a fixed support.

The device has several important advantages. It is simple in construction, can be produced at a low cost, and can be folded into small compass for convenience when not in use. The folding rests make it possible to easily position the board to be cut and to 105 operate the device.

The invention is not to be understood as

restricted to the precise details shown and described, since these can be modified by the skilled mechanic without departing from the spirit and scope of the invention.

5 Having thus described the invention, what I claim as new, and desire to secure by Letters Patent, is—

- 10 1. In a miter-box the combination with a support and saw-guide of a side guide pivotally connected to the support and laterally adjustable to vary its angular relation with respect to the guide, and a rest pivotally sustained to swing vertically and be folded alongside of the side guide.
- 15 2. In a miter-box the combination with a support and saw-guide of a side guide pivotally connected to the support and laterally adjustable to vary its angular relation with respect to the guide, a rest pivoted to the side guide, and an adjustable connection between the side guide and the support, for holding the guide in assigned position.
- 20 3. In a miter-box the combination with a support and saw-guide of a pair of side guides each hinged to the support and laterally adjustable with respect thereto, and a rest hinged to each of the side guides.
- 25 4. In a miter-box the combination with a support and saw-guide of a pair of side guides adjustably held with respect to the saw-guides, a rest hinged to each of the side guides and an adjustable connection for equidistantly shifting the side guides with respect to the saw-guides.

5. In a miter-box the combination with a support and saw-guide of a pair of side guides adjustably held with respect to the saw-guides and a rest hinged to each of the side guides to swing into substantially parallel relation with respect to the side guide. 35

6. In a miter-box the combination with a support, comprising a pair of bars, and a saw-guide of a pair of side guides adjustably connected to the support, a block held between said bars, a link connection between the block 40 and each of the side guides and means for forcing the bars together to hold the block in assigned position. 45

7. The combination of a frame or support, comprising a pair of members, each comprising a base-bar, an upright, and a top bar, a saw-guide being formed therebetween, a side guide pivoted to the frame and a rest hinged to the side guide. 50

8. The combination of a frame or support comprising a pair of members, each having a base-bar, an upright, and a top bar, a saw-guide being formed between the members, a pair of side guides pivoted to the frame, a rest pivoted to each of the side guides and an 55 adjustable connection for equidistantly shifting the side guides with respect to the saw-guide. 60
